MECHANICAL MOVEMENT

Lowell F. Hammand, Washington, D. C.

Original application November 18, 1941, Serial No. 419,525. Divided and this application March 21, 1942, Serial No. 435,724

5 Claims. (Cl. 74—2)

(Granted under the act of March 3, 1883, as amended April 30, 1928; 370 O. G. 757)

The invention described herein, if patented, may be manufactured and used by or for the Government for governmental purposes, without the payment to me of any royalty thereon.

The present invention relates to mechanical movements such as latching devices, and more particularly to a simple and novel arrangement of parts whereby relatively great loads may be securely latched against accidental release, yet positively released in response to latch-actuating forces of extremely small magnitude.

In most conventional latch structures, latching surfaces are provided that frictionally engage each other and prevent relative movement between stationary and movable parts of the mechanism. In all well known structures of this character the force required to cause the latch to release is more or less proportionate to the magnitude of the load acting on the latch surfaces, that is, the greater pressure that exists on the latch surfaces, the greater the friction between these surfaces, and the larger the force that will be required to effect release.

It has long been one aim of machine designers to provide a simple type of latching structure arranged to sustain the load of a great weight or heavy spring pressure and yet so designed and constructed that it was capable of positive and unfailing release operation in response to very small forces.

The utility of a satisfactory device of this character should be entirely obvious since any device that reduces the operating force required to release a latch structure will necessarily improve the operating characteristics of any mechanism including a latch arranged to be actuated by small forces.

The latch comprising the subject matter of the present invention is shown and described in connection with a gasoline dispensing nozzle and is associated with the nozzle in such a manner that the heavy load of the valve actuating spring may be positively controlled by slight fluctuations in atmospheric pressure in a diaphragm control system, and while such an arrangement is well adapted to illustrate the utility of and the necessity for a latching device as disclosed in this application, it should be understood that the nozzle structure is described by way of illustration rather than by way of limitation and that the teachings of the present invention are equally applicable throughout the entire field of mechanics and in connection with any device having a heavy load to be released by comparatively minute forces.

A primary object of the present invention is to provide a novel and improved mechanical movement constituting a latching structure adapted to maintain itself against a relatively great load and to release said load in response to forces of extremely small magnitude.

A further object of the invention is to provide a latching mechanism constituting a series of latches wherein the primary latch maintains the mechanism against release and a secondary latch prevents release of the first, the arrangement being such that the primary latch is unstable in that it is not self-maintaining and will automatically release unless maintained in position by the secondary latch.

A further object of the invention is to provide a series of latches including a primary unstable latch and a secondary latch together with force-reduction levers whereby the secondary latch has a mechanical advantage over the primary and whereby the latch actuating means has a mechanical advantage over the secondary latch.

A further object of the invention is to provide a mechanical movement including a series of latches having an unstable primary latch in combination with a secondary latch and actuating means for the primary latch arranged to concurrently release the primary latch and apply force to assist in its releasing movement.

A still further object of the invention is to provide a mechanical latching mechanism of the type described including a relatively few parts of rugged construction and simple mechanical operation and adapted to economical methods of manufacture.

The present application is a division of my pending application, Serial No. 419,525, filed November 18, 1941, and, while the claims of this application will be limited to the features of the mechanical movement used as a latching device in the parent application, it is believed desirable to fully illustrate the gasoline dispensing nozzle structure of the parent case, in order to give a clear understanding of one adaptation of the present claimed invention. It should be noted, however, that this case is directed to a mechanical movement that is by no means limited in utility to gasoline dispensing equipment, but which is of broader scope, and extends to any one of

the various fields of mechanics in which latching structures are used.

Referring now more particularly to the drawing,

Fig. 1 is a longitudinal sectional view of a gasoline dispensing nozzle having a latching device

constructed in accordance with the teachings of the present invention, and

Fig. 2 is a fragmental longitudinal sectional view of a modified form of the invention.

The nozzle structure illustrated includes a valve housing or body portion generally indicated at 10. The valve body 10 has a tubular handle portion 11 including an inlet passageway 12, and a neck portion 13 including an outlet passageway 14 having a restricted Venturi section 15 and terminating in a forward end constituting a mounting collar 16 for the dispensing spout 17. The valve body is provided with a valve seat 21 interconnecting the inlet passageway 12 with the outlet passageway 14. The valve seat 21 is closed by a valve 22 having a valve stem 23 arranged to extend exteriorly of the valve body 10 so that the lower extremity 24 of the valve stem will be outside of the valve body and adapted for manual actuation. Preferably, a gland or other suitable sealing structure (not shown) is arranged to be tightened around the stem 23 by means of the sealing cap 25. The valve 22 is normally forced into firm engagement with the valve seat 21 by a relatively heavy coiled compression spring 26 having its upper end supported by the threaded closure cap 27 and having its lower end bearing directly against the valve 22. The closure cap 27 is threaded into the valve body and is preferably provided with a sealing gasket 28 and drilled at 29 to provide a guide for the upper end of the valve stem. It is contemplated that the valve 22 is to be opened manually, and to this end a valve operating lever 32 is pivoted on a supporting pivot 33 positioned somewhat forwardly of the lower extremity 24 of the valve stem. The valve operating lever 32 is offset at 34 so that the handle portion remote from the supporting pivot 33 will lie substantially parallel with the handle portion 11 of the valve body, so that the operator may grasp the handle 11 and the valve handle 32 in one hand and open the valve by drawing the lever 32 toward the valve body. The actuating lever 32 is protected against accidental opening or damage by a lever guard 35 secured to the end of the handle portion 11 by any convenient means, and including a relatively straight portion 37 spaced apart from the valve body and extending forwardly in a position more or less parallel with the handle portion 11. The forward curved end 38 of the handle guard is arranged to be secured to the lower side of the valve neck 13 by a plurality of cap screws (not shown), which extend through the flange 39. The forward portion of the handle guard 35 is provided with a pair of relatively wide side walls 41 spaced apart from each other to define a cavity 42 in the forward portion of the valve guard in front of the valve stem and below the neck 13 and outlet passageway 14 for the purposes to be herein-after described.

The lower portion of the forwardly extending neck 13 of the valve body is widened to provide a rarified air cavity 45 over which a flexible fabric diaphragm 46 is clamped by a suitable flange 47. The diaphragm 46 may be of any resilient material but is preferably formed of multiple thicknesses of thin cloth treated in such a manner as to make it impervious to air and commonly known in the trade as "airplane cloth." The diaphragm 46 is circular in shape so that it entirely closes the lower side of the aperture 45. It is provided with a pair of center plates 48 to reinforce the fabric diaphragm and

to provide a mounting for a post 49 to which the latch release mechanism is attached.

The rarified air cavity 45 is interconnected with the venturi 15 by suction ports 50 and 51 so that the flow of liquid through the discharge passageway of the nozzle will withdraw some of the air from the air chamber 45 of the valve body. When the device is in use, the air sucked from the chamber 45 through the suction ports will be replaced by air entering the side port 52 of the nozzle spout 17.

In the present structure, the port 51 is plugged at its rear end by the tapered plug 52 and communication with the interior of the chamber 45 is established by the port 50 extending angularly from the port 51 to a point adjacent the lower forward edge of the diaphragm 46. With this arrangement the suction action of the Venturi tube 15 will remove any accumulation of liquid gasoline within the chamber 45, so that any quantities of gasoline drawn upwardly through the tube 50 will be immediately ejected through the ports 50 and 51 and into the stream of liquid, in order that the passageways will always be open for the free venting of air to the chamber 45.

The air from the port 52 enters through the orifice 53 in the block 54 secured on the inner circumference of the spout, and passes thence through the vent tube 55 which extends upwardly through the spout 17 and communicates with the air chamber 45 through the air inlet port 59. The block 54 is provided with an annular valve seat 55 and a screw-threaded adjusting screw 56 is arranged with a needle valve 57 adapted to be adjustably moved toward the valve seat 55 to provide an adjustment for the restriction of the vent passageway. It will be noted that the block 54 is positioned entirely within the nozzle spout 17 and is therefore entirely protected against accidental damage, but the screw 56 is parallel with the axis of the nozzle spout and may be easily reached by inserting a screw driver in the open lower end of the spout. By this arrangement, the restriction of the air inlet to the cavity 45 may be adjusted so that the device will be readily responsive to specified changes in pressure.

The subject matter claimed in the present application resides in the features of the mechanical movement associated with the supporting pivot 33 on which the valve control handle is mounted, in order that the relatively small atmospheric force actuating the shut-off diaphragm 55 may be utilized to release the comparatively large force of the coiled compression spring 26 and force the valve 22 into closed position. To accomplish this result, the valve pivot pin 33 is mounted in a pair of slots 61 provided in each of the side walls 41 of the linkage cavity 42. These slots 61 act as guides for the supporting pivot 33 so that when it is not maintained by mechanism hereinafter described, the forward end of the valve operating lever 32 may snap outwardly responsive to the outward force of the valve stem, so that the valve 22 will be in closed position notwithstanding the fact that the rear end of the valve operating lever 32 is moved toward the handle portion 11 of the valve body.

The supporting pivot 33 also extends through a shiftable pivot retainer 62 adapted to partially encircle a roller 63 rotatably mounted on the cross pin 64 extending between the two side walls 41 of the linkage cavity 42. The upper end of the pivot retainer 62 includes a latching surface

65 arranged to engage and be secured by a latching surface 66 formed on the latch release lever 67. The lever 67 is pivotally mounted on a stationary pivot 68 extending between the walls 41 of the linkage cavity 42 and has its outer end pivotally mounted on the diaphragm post 48 by a pivot pin 69. The pin 69 also carries one end of a coiled compression spring 71 which extends downwardly and has its lower end secured to a side projection 73 formed on the latch retainer 62. The curved surface 74 of the latch retainer 62 partially encircles the roller 63 to provide an unstable roller type latch, the arrangement being such that while the roller 63 and its mounting pin 64 restrain the supporting pivot 33 against downward movement in the slot 61, yet the angle of engagement between the roller 63 and the curved surface 74 of the latch retainer is such that the force of the compression spring 26 will exert a definite bias on the latch retainer, tending to move it to the right as viewed in the drawing, unless this movement is prevented by some outside means. It will be understood, however, that the magnitude of the force tending to bias the latch to released position will be very small as compared with the force exerted by the spring 26.

The upper extension of the latch retainer constitutes, in effect, a lever with the supporting pivot 33 as a fulcrum and with the force acting at the curved surface 74, so that the upper portion 65 of the lever will have a definite mechanical advantage over the latching surfaces 74 and so that the forces tending to bias the latch retainer 62 toward released position may be readily overcome by a very light force at the upper end 65 of the latch retainer. Thus, the effective pressure between the latching surfaces 65 and 66 will be extremely small and the latching may be easily released by the operation of the diaphragm 46 even though the pressure differential on the opposite sides of the diaphragm is comparatively small.

The operation of the device is as follows:

The normal position of all parts of the structure is as shown in Fig. 1 of the drawing and, to operate the device, the operator will grasp the nozzle by the handle portion 11 and draw the rear end of the valve-operating lever 32 inwardly to bear against the lower portion 24 of the valve stem and raise the valve 22 from the seat. The liquid will then be free to flow through the passageway 12 into the passageway 14 through the Venturi tube 15 and outwardly through the nozzle spout 17 and into the container. During this time the action of the Venturi tube 15 will withdraw air from the air chamber 45, but inasmuch as the air chamber 45 is vented through the air inlet 52 and vent tube 58, the pressure within the air chamber 45 will not be substantially reduced and the diaphragm 46 will not be caused to operate. However, when the level of the liquid in the container being filled rises to a point above the end of the spout 17, the liquid will close the orifice 52 or the restricted needle valve 57 and, since the flow of liquid through the restricted orifice will be far less than the flow of air through the same orifice, the vent 58 will be, to all intents and purposes, closed by the rising level of the liquid. When this occurs, the continued action of the Venturi tube 15 will continue to withdraw air through the suction ports 50 and 51 and cause a substantial reduction of pressure in the air chamber 45 so that the atmospheric pressure of the surrounding air (which

is in communication with the lower surface of the diaphragm 46 through the linkage cavity 42) will force the diaphragm 46 upwardly against the comparatively light resistance of the spring 71. 5 The cross pin 69 acts as a pivot for the anchored end of the pressure reduction lever 67, so that when the outer end of the lever 67 is drawn upwardly, the latching notch 66 is disengaged from the upper end 65 of the retainer 62. It will be 10 noted, in passing, that the latching notch 66 is positioned at a point less than half of the distance between the pivot pin 68 and the diaphragm post pivot 69 so that the movement of the diaphragm has a decided mechanical advantage 15 over the latching surfaces and a very small effort on the diaphragm is sufficient to overcome the friction incident to the engagement of the latch, so that the release operation of the mechanism will be entirely positive, notwithstanding 20 the fact that the pressure differential on the opposite sides of the diaphragm may be rather small.

When the latch 66 disengages the upper end of the retainer 62, the force of the coiled compression spring 26 of the main valve 22 will act on the unstable latch 63-74 to release the pivot 33 and snap it to the lower end of the guide slots 61 to close the valve. This action will be readily understood when it is recalled that the latch 63-74 is unstable. Thus, when the lever 32 is 30 operated, the force of the compression spring 26 will urge the supporting pivot 33 downwardly in the slot 61 and will tend to bias the latch toward its released position. It will be understood, of course, that the force tending to bias the latch to its released position will be extremely small as compared to the total force of the spring 26, but it will nevertheless permit the mechanism to release when the secondary latch 65-66 is disengaged. As this operation takes place, it is obvious that the spring 26 will instantly close the valve 22 and shut off the flow of liquid in time to prevent the container being filled from overflowing.

45 When the flow of liquid through the Venturi tube 15 is discontinued, the pressure on the opposite sides of the diaphragm 45 will automatically equalize, and the spring 71 will draw the diaphragm 46 outwardly and downwardly to the 50 position illustrated in Fig. 1.

On release of the lever 32 the coiled spring 71 will draw the latch retainer 62 upwardly and, inasmuch as the outer extension 73 of the latch retainer 62 is a considerable distance from the 55 pivot 33, the spring will tend to move the upper end 65 of the retainer inwardly to the left until it engages the notch 66, at which time the spring 71 will move the lever downwardly so that the notch will prevent return movement of the latch 65; thus, the single spring 71 serves the multiple functions of drawing the diaphragm downwardly, returning the latch 66 to position, drawing the pivot 33 and latch retainer upwardly and swinging the pivot latch retainer 62 to the left 60 about the pivot 33 to cause engagement of the latched surfaces 65 and 66. In this manner the single spring 71 comprises spring means for accomplishing four separate functions, though it will be understood that it is a matter of simple mechanical skill to provide separate springs to accomplish each of the aforementioned functions.

70 The device illustrated in Fig. 2 is similar to that shown in Fig. 1 with the exception that the latch retainer 81 is provided with a latching sur-

face 82 comprising an inclined cam surface at an obtuse angle with respect to the direction of release movement of the latch and the latching surface 82 is arranged to engage an inclined cam surface 83 on a stationary latch block 84. This structure constitutes an unstable latch wherein a downward force on the latch pivot 33 will tend to bias the retainer toward its released position and will release the latch unless otherwise secured. The upper end of the latch is otherwise secured, however, by the latching engagement between the inclined cam surface 85 of the latch retainer and a corresponding inclined cam surface 86 of the latch lever 87 mounted on the cross pivot 88. The inner end of the lever 87 is mounted for pivotal movement on a pin 88 extending between the side walls 41 of the linkage cavity and the outer end of the lever is connected to the diaphragm post 49 by a pivot pin 89. In this construction it will be noted that the primary latch comprising the latch surfaces 82 and 83 cooperate to form an unstable latch which will be biased toward released position and will release unless maintained by an external force, and that the secondary latching surfaces 85 and 86 are similarly arranged. Accidental release of the secondary latch is prevented, however, by a light coiled compression spring 91 positioned within the air chamber 45 and arranged to urge the diaphragm 46 and lever 87 downwardly. The arrangement is such that the spring 91 is sufficient to overcome the extremely small force tending to bias the latch 85-86 to released position and the unstable characteristics of this latch only tend to provide for easy and positive release whenever the pressure differential on the diaphragm 46 becomes sufficient to overcome the downward force of the spring 91.

A return spring 92 is mounted on the cross pin 93 and secured to a side pin 94 on the latch retaining element 84 and is arranged to lift the supporting pivot 33 to return it to the upper end of the slot when the handle is released and to exert a counterclockwise urge on the latch retainer 81 causing it to engage the latching surface 82 above the inclined cam surface 83 and causing its upper end to move beyond the latching surface 86 so that the return movement is effectually prevented.

It has been previously mentioned that the latching structures 63-74 and 82-83 are so arranged that they are biased toward released position by the force of the spring 26. It is desirable that the magnitude of the force component acting as a bias be quite small in order that the friction incident to the release of the secondary latches be as small as possible, but it will also be appreciated that if it is too small the friction between the cooperating surfaces of the primary latch may cause the latch to fail to release.

In the present invention, means are provided whereby the cooperating surfaces of the primary latches may be unfailingly released, even though shaped to resolve the force of the spring 26 into a biasing force of far less magnitude than would be required by the structure heretofore described. This desirable object is accomplished by the novel combination of the structure heretofore described and a latch actuator mechanism to actively force the primary latch to release concurrently with the release of the secondary latch. For this purpose the lever 67 is provided with a short latch actuator or push-off arm 75 so that as the latch 65-66 is released the actuator 75 will strike the

upper end 65 of the retainer and actively urge the primary latch 63-74 to release. In the structure illustrated in Fig. 2, the lever 87 is provided with a short latch actuator 95 adapted to function in an identical manner.

By this arrangement it is entirely feasible to shape the surfaces of the primary latch to exert a bias force that is almost, but not quite, sufficient to overcome the friction of the latching surfaces and cause the primary latch to release. This will mean that there will be no effective force acting between the secondary latch surfaces, so these will release without friction, and since the primary latch is already biased to release, it will require only a touch from the actuator.

From the foregoing, it will be apparent that by following the teachings of the present invention, a novel and improved mechanical latch movement may be provided whereby the release of relatively great forces, such as exerted by the load of the heavy shut-off valve spring may be positively controlled by a simple, rugged mechanism adapted to be operated by a comparatively minute effort.

It will also be seen that the mechanical movement here disclosed is well suited to the control of relatively large loads responsive to controlling forces of minute magnitude, since the force acting on the pin 33 is primarily maintained by the unstable latch, but the small biasing force due to the inclination of the surfaces will tend to release the latch unless secured by additional means. The secondary latch constitutes the additional means for securing, but since the biasing force is of extremely small magnitude, the friction acting between the latching surfaces of the secondary latch will be so small as to present no substantial resistance to actuation of the mechanism by the diaphragm 46. Thus, the relatively small forces exerted by the diaphragm are entirely effective to release the heavy load exerted by the valve spring 26, with the result that the structure may be arranged to positively respond to the small differences in pressure incident to the submerging of the nozzle tip beneath the surface of the liquid.

Further, the entire latching structure is simple and compact, so that it may be positioned within the angle "A" in Fig. 1 of the drawing, so as to add to the streamlined appearance of the device.

While I have shown and described a preferred embodiment of the present invention, I am aware that it is subject to numerous modifications and variations without departing from the invention spirit and I therefore wish to be limited only by the scope of the appended claims.

Having thus described my invention, I claim:

1. A latching device including an anchor element and a supporting pivot, said anchor element and supporting pivot being relatively shiftable with respect to each other, guide means to establish a predetermined path of movement for said supporting pivot, and a connecting link extending between the anchor element and the supporting pivot; a cam surface on the anchor element, a cam surface on the connecting link, the arrangement and construction being such that the cam surfaces of said anchor element and said connecting link contact each other and provide an unstable latch between the anchor element and the connecting link, the said cam surfaces being angularly inclined with respect to the link so that forces acting to separate the supporting pivot and anchor will bias the latch toward released position, a secondary latching device associated with

the connecting link and arranged to maintain the cam surfaces of the link and anchor in contact and to prevent movement of the connecting link with respect to the anchor element, a latch actuator adapted to exert force against the connecting link in a lateral direction to cause the cam surfaces of the link and anchor to move out of engagement, and means to concurrently release the secondary latch and operate the toggle actuator to actively urge the link to disengaged position.

2. A latching device including an anchor element and a supporting pivot, said anchor element and supporting pivot being relatively shiftable with respect to each other, and a connecting link extending between the anchor element and the supporting pivot; a cam surface on the anchor element, a cam surface on the connecting link, the arrangement and construction being such that the cam surfaces of said anchor element and said connecting link contact each other and provide an unstable latch between the anchor element and the connecting link, the said cam surfaces being angularly inclined with respect to the link so that forces acting to separate the supporting pivot and anchor will bias the latch toward released position, but so the bias will be insufficient to overcome the friction between the cam surfaces, a secondary latching device associated with the connecting link and arranged to maintain the cam surfaces of the link and anchor in contact and to prevent movement of the connecting link with respect to the anchor element, a latch actuator adapted to exert force against the connecting link in a lateral direction to cause the cam surfaces of the link and anchor to move out of engagement, and means to concurrently release the aforementioned secondary latch and operate the toggle actuator to actively urge the link to disengaged position.

3. A latching device including an anchor element and a supporting pivot, said anchor element and supporting pivot being relatively shiftable with respect to each other, and a connecting link extending between the anchor element and the supporting pivot; a cam surface on the anchor element, a cam surface on the connecting link, the arrangement and construction being such that the cam surfaces of said anchor element and said connecting link contact each other and provide an unstable latch between the anchor element and the connecting link, the said cam surfaces being angularly inclined with respect to the link so that forces acting to separate the supporting pivot and anchor will bias the latch toward released position; a secondary latching device associated with the connecting link and arranged to maintain the cam surfaces of the link and anchor in contact and to prevent movement of the connecting link with respect to the anchor element, a latch actuator adapted to exert force against the connecting link in a lateral direction to cause the cam surfaces of the link and anchor to move out of engagement, and means to concurrently release the secondary latch and operate the toggle actuator to actively urge the link to disengaged position.

4. A latching device including an anchor element and a supporting pivot, said anchor element and supporting pivot being relatively shift-

able with respect to each other, and a connecting link extending between the anchor element and the supporting pivot; a cam surface on the anchor element, a cam surface on the connecting link, the arrangement and construction being such that the cam surfaces of said anchor element and said connecting link contact each other and provide an unstable latch between the anchor element and the connecting link, the said cam surfaces being angularly inclined with respect to the link so that forces acting to separate the supporting pivot and anchor will bias the latch toward released position; a secondary latching device associated with the connecting link and arranged to maintain the cam surfaces of the link and anchor in contact and to prevent movement of the connecting link with respect to the anchor element, a latch actuator adapted to exert force against the connecting link in a lateral direction to cause the cam surfaces of the link and anchor to move out of engagement, and means to concurrently release the secondary latch and operate the toggle actuator to actively urge the link to disengaged position.

5. A latching device including an anchor element and a supporting pivot, said anchor element and supporting pivot being relatively shiftable with respect to each other, and a connecting link extending between the anchor element and the supporting pivot and adapted for arcuate movement relative to the supporting pivot whereby the connecting link will be guided in an arc having the axis of the pivot as its center; a cam surface on the anchor element, a cam surface on the connecting link, the arrangement and construction being such that the cam surfaces of said anchor element and said connecting link contact each other and provide an unstable latch between the anchor element and the connecting link, the said cam surfaces being angularly inclined with respect to the link so that forces acting to separate the supporting pivot and anchor will bias the latch toward released position, but so the bias will be insufficient to overcome the friction between the cam surfaces and the supporting pivot will be restrained against shifting movement with respect to the anchor element; a secondary latching device associated with the connecting link and arranged to maintain the cam surfaces of the link and anchor in contact and to prevent movement of the connecting link with respect to the anchor element, a latch actuator adapted to exert force against the connecting link in a lateral direction to cause the cam surfaces of the link and anchor to move out of engagement, and means to concurrently release the secondary latch and operate the toggle actuator to actively urge the link to disengaged position, said means including a pivoted lever having a latch notch adapted to move in one direction to release the latch and an actuating arm adapted to move in a direction normal to the movement of the latch notch to urge the link toward released position.

6. A latching device including an anchor element and a supporting pivot, said anchor element and supporting pivot being relatively shiftable with respect to each other, and a connecting link extending between the anchor element and the supporting pivot and adapted for arcuate movement relative to the supporting pivot whereby the connecting link will be guided in an arc having the axis of the pivot as its center; a cam surface on the anchor element, a cam surface on the connecting link, the arrangement and construction being such that the cam surfaces of said anchor element and said connecting link contact each other and provide an unstable latch between the anchor element and the connecting link, the said cam surfaces being angularly inclined with respect to the link so that forces acting to separate the supporting pivot and anchor will bias the latch toward released position, but so the bias will be insufficient to overcome the friction between the cam surfaces and the supporting pivot will be restrained against shifting movement with respect to the anchor element; a secondary latching device associated with the connecting link and arranged to maintain the cam surfaces of the link and anchor in contact and to prevent movement of the connecting link with respect to the anchor element, a latch actuator adapted to exert force against the connecting link in a lateral direction to cause the cam surfaces of the link and anchor to move out of engagement, and means to concurrently release the secondary latch and operate the toggle actuator to actively urge the link to disengaged position, said means including a pivoted lever having a latch notch adapted to move in one direction to release the latch and an actuating arm adapted to move in a direction normal to the movement of the latch notch to urge the link toward released position.
